NUMBER TRANSMITTING ARRANGEMENT
Otto Modersohn, Volkmarode über Braunschweig, Germany, assignor to Olympia Werke A.G., Wilhelmshaven, Germany

Filed Nov. 29, 1960, Ser. No. 72,418

Claims priority, application Germany Dec. 1, 1959
7 Claims. (Cl. 235—61)

The present invention relates to a number transmitting arrangement, and more particularly to an arrangement for transmitting information representing a multi-order number to a remote station.

One object of the present invention is to provide an arrangement permitting simultaneous transmission of a plurality of electric impulses respectively representing digits of a plurality of orders.

Another object of the present invention is to provide a transmitting arrangement capable of simultaneous transmission of several impulses with a minimum of electric connections.

Another object of the present invention is to provide a compact transmitting arrangement which can be built into a conventional calculator.

Another object of the present invention is to provide a reliably and rapidly operating transmitting arrangement for connecting at least two calculators so that a number introduced into one of the calculators is transmitted to the other calculator, and stored in the counter mechanism of the same.

With these objects in view, a transmitting arrangement according to one embodiment of the present invention comprises a set of first conductors; a set of second conductors which preferably cross the first conductors to form with the same crossing points; a set of electric actuators, which are respectively connected to the first conductors; a set of voltage sources respectively connected to the second conductors and to the actuators; and means for connecting selected first conductors to selected second conductors, preferably by switches or connectors disposed at the crossing points of the first and second conductors.

The conductors of one set represent the orders of a number, and the conductors of the other set represent digits. Consequently, the crossing points between the conductors represent digits in their respective orders. When the first and second conductors are connected at selected crossing points, a digit and an order are thus selected, and an impulse passes from the respective voltage source to the respective correlated electro-magnetic actuator independently of the other voltage sources. In this manner, all impulses can be simultaneously transmitted to electro-magnetic actuators which are located at a remote station to actuate the input means of a calculator simultaneously in several orders.

In the preferred embodiment of the invention, the voltage sources are constituted by a set of secondary windings of a transformer, each secondary winding being connected through a rectifier to a conductor which represents an order, and to a line connected to a group of electro-magnetic actuators, each of which is also connected to a digit-representing conductor.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

FIG. 1 is a perspective view illustrating a full-key calculator provided with means for transmitting and receiv-

2

ing information in accordance with the present invention; and

FIG. 2 is a diagram illustrating the electric circuit of an arrangement according to the present invention.

Referring now to the drawings, and more particularly to FIG. 1, a conventional full-key calculator has a keyboard *q*, each key of which is shown to be provided with an electro-magnetic actuator *o* having a movable actuating member *r*. Part of the casing of the machine is omitted to show the interior of the machine which contains a counter gear *h* meshing with a transfer gear *i* which is in meshing engagement with a rack bar *k*. The rack bar *k* is pivotally mounted in the machine, and is operated by a cam *n* so that a rotation of cam *n* will effect movement of the projection *m* on bar *k* to and from a lower operative position.

A matrix is mounted on an insulating plate *p*, and comprises a set of first parallel conductor bars *b*, and a set of parallel second conductor bars *a* which cross conductors *b* at right angles. Conductors *a* and *b* are provided with bores at the crossing points, and switch pins *f* are located in these bores and are shiftable between an inoperative circuit-breaking position, and a circuit closing position in which they make contact with both conductors at the crossing point, and consequently connect the respective crossing conductors to each other.

Bar *k* extends in the direction of the conductor bars *a*, and when the counter gear *h* is operated to represent a digit, the projection *m* will move along the respective conductor *a* until located above a switch pin *f* on the crossing point with a digit-representing conductor *b*. When cam *n* moves projection *m* to its operative position, the respective switch pin *f* is shifted to its circuit-closing position, and a connection is established between the respective conductor *a* representing an order, and the respective conductor *b* representing a selected digit.

This operation is carried out in all orders of a number introduced into the storage means of the calculator, so that the respective number is represented in the matrix *a*, *b*, *f*.

A transformer having a primary winding *e* and a set of secondary windings *d* is disposed in the casing of the calculator, and the primary winding is connected to a source of alternating voltage. As also shown in FIG. 2, each secondary winding *d* is connected by a wire *3* to a rectifier *c* whose other terminal is connected by a wire *4* to a correlated conductor *a*. Since the conductors *a* are respectively associated with different orders, each secondary winding, which constitutes an independent source of voltage, is also associated with an order.

The other ends of the secondary windings are respectively connected by electric connections *2* to a group *G* of electro-magnetic actuators *g*, as best seen in FIG. 2, only one actuator being shown in FIG. 1, but as shown in FIG. 2, a set of groups *G* of actuators *g* is provided, only three group *G* of the set being shown for the sake of simplicity. The electro-magnetic actuators *g* are located at a remote station, for example at a second calculator. The keys of the second calculator at the remote station may be operated by the electro-magnetic actuators *g* in the same manner as the keys of the calculator shown in FIG. 1 are operated by an electro-magnetic actuator *o*.

The transmitting arrangement of the present invention operates in the following manner: A numerical value introduced into the counter mechanism of the calculator is transmitted by gear *i* to the rack bar *k* so that the projection *m* assumes a position located over the switch pin *f* at the crossing point with the conductor *b* associated with the respective digit. When cam *n* actuates rack bar *k*, switch pin *f* is shifted to its circuit-closing position connecting the respective two conductors *a* and *b* at the crossing point. In this manner, a circuit is closed, and an im-

pulse passes from the respective secondary winding *d*, rectifier *c*, connection 4, the respective conductor *a* of the respective order, switch pin *f*, the respective conductor *b* associated with the introduced digit, the electro-magnetic actuator *g* connected to the respective conductor *b*, and through line 2 back to the secondary winding *d*.

In accordance with the preferred embodiment of the invention, several second windings provide independently of each other the voltages for the group of actuators. Since a group digit-representing actuators is connected to each independent voltage source *d*, a circuit can be completed in each order, so that impulses representing numbers can be transmitted in all orders simultaneously, resulting in a very rapid transmission of a multi-order number between two calculators.

The transmitting calculator may also receive impulses from a remote station, and be actuated by electro-magnetic actuators *o*, only one of which is shown in FIG. 1.

It will be understood that each of the elements described above, or two or more together, may also find a useful application in other types of number transmitting arrangements differing from the types described above.

While the invention has been illustrated and described as embodied in a transmitting arrangement providing an independent voltage source for each order of a calculator, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. A transmitting arrangement for simultaneously transmitting multi-order numbers between two stations, and comprising, in combination, a set of first conductors and a set of second conductors located at one of said stations, the conductors of one set respectively representing digits and the conductors of the other set respectively representing orders; a set of groups of electro-magnetic actuators located at the other station, each actuator being adapted to operate an element located at said other station, said actuators of each group being respectively connected to said first conductors; a set of voltage sources located at said first station respectively connected to said second conductors and respectively connected to said groups of actuators so that each group of actuators has a different voltage source; and means for simultaneously connecting selected first conductors to said second conductors so that one actuator of each group is energized by the correlated voltage source independently of the other voltage sources when the first conductor connected thereto is connected to one of said second conductors whereby a plurality of actuators belonging to different groups can be simultaneously energized by different voltage sources.

2. A transmitting arrangement for simultaneously transmitting multi-order numbers between two stations, and comprising in combination, a set of first conductors and a set of second conductors located at one of said stations, the conductors of one set respectively representing digits and the conductors of the other set respectively representing orders, said first and second conductors crossing each other at crossing points representing digits in the respective orders; a set of groups of electro-magnetic actuators located at the other station, each actuator being adapted to operate an element located at said other station, said actuators of each group being respectively connected to said first conductors; a set of voltage sources located

at said first station respectively connected to said second conductors and respectively connected to said groups of actuators so that each group of actuators has a different voltage source; a plurality of switch means respectively located at said crossing points, each switch means being shiftable to and from a circuit closing position for connecting the respective first and second conductors at the respective crossing point to each other; and means for shifting selected switch means to said circuit closing position so that one actuator of each group is energized by the correlated voltage source independently of the other voltage sources when the first conductor connected thereto is connected to one of said second conductors whereby a plurality of actuators belonging to different groups can be simultaneously energized by different voltage sources.

3. A transmitting arrangement for simultaneously transmitting multi-order numbers between two stations, and comprising, in combination, a set of first conductors and a set of second conductors located at one of said stations, the conductors of one set respectively representing digits and the conductors of the other set respectively representing orders, said first and second conductors crossing each other at crossing points representing digits in the respective orders; a set of groups of electro-magnetic actuators located at the other station, each actuator being adapted to operate an element located at said other station, said actuators of each group being respectively connected to said first conductors; a set of voltage sources located at said first station respectively connected to said second conductors and respectively connected to said groups of actuators so that each group of actuators has a different voltage source; and means for simultaneously connecting at said crossing points selected first conductors to said second conductors so that one actuator of each group is energized by the correlated voltage source independently of the other voltage sources when the first conductor connected thereto is connected to one of said second conductors whereby a plurality of actuators belonging to different groups can be simultaneously energized by different voltage sources.

4. A transmitting arrangement for simultaneously transmitting multi-order numbers from a first calculator to a second calculator located at a station remote from said first calculator, the arrangement comprising, in combination, a set of parallel first conductors located in said first calculator and respectively representing digits; a set of second conductors in said first calculator extending parallel to each other and at right angles to said first conductors and respectively representing orders, said first and second conductors crossing each other at crossing points representing digits in the respective orders; a set of groups of electromagnetic actuators located at said remote station for operating elements of said second calculator, said electro-magnetic actuators of each group being respectively connected to said first conductors; a set of voltage sources located at said first calculator respectively connected to said second conductors and respectively connected to said groups of electro-magnetic actuators so that each group of actuators has a different voltage source; a plurality of switches respectively located at said crossing points, each switch being shiftable to and from a circuit closing position for connecting the first and second conductors crossing at the respective crossing point to each other; and means adapted to be actuated under control of the counter mechanism of said first calculator for shifting selected switches to said circuit closing position for connecting selected first conductors to selected second conductors so that one actuator of each group is energized by the correlated voltage source independently of the other voltage sources when the first conductor connected thereto is connected to one of said second conductors whereby a plurality of actuators can be simultaneously energized by different voltage sources.

5. A transmitting arrangement for simultaneously transmitting multi-order numbers from a first calculator

to a second calculator located at a station remote from said first calculator, the arrangement comprising, in combination, a set of first conductors located in said first calculator and respectively representing digits; a set of second conductors in said first calculator and respectively representing orders; a transformer located at said first calculator and including a primary winding adapted to be connected to a source of alternating voltage, and a set of secondary windings, said secondary windings having first ends respectively connected to said second conductors and second ends respectively connected to said electro-magnetic actuators; a set of voltage sources located at said first calculator respectively connected to said second conductors and respectively connected to said groups of electro-magnetic actuators so that each group of actuators has a different voltage source; and means for connecting selected first conductors to selected second conductors so that one actuator of each group is energized by the correlated secondary winding independently of the other secondary windings when the first conductor connected thereto is connected to one of said second conductors whereby a plurality of actuators can be simultaneously energized by different voltage sources.

6. An arrangement as set forth in claim 5 and including a set of rectifiers connected between said first ends of said secondary windings and said second conductors.

7. A transmitting arrangement for simultaneously transmitting multi-order numbers from a first calculator to a second calculator located at a station remote from said first calculator, the arrangement comprising, in combination, a set of parallel first conductors located in said first calculator and respectively representing digits; a set of second conductors in said first calculator extending parallel to each other and at right angles to said first conductors and respectively representing orders, said first

30

35

and second conductors crossing each other at crossing points representing digits in the respective orders; a transformer located at said first calculator and including a primary winding adapted to be connected to a source of alternating voltage, and a set of secondary windings, said secondary windings having first ends respectively connected to said second conductors and second ends respectively connected to said electro-magnetic actuators; a set of voltage sources located at said first calculator respectively connected to said second conductors and respectively connected to said groups of electro-magnetic actuators so that each group of actuators has a different voltage source; a plurality of switches respectively located at said crossing points, each switch being shiftable to and from a circuit closing position for connecting the first and second conductors crossing at the respective crossing point to each other; and means adapted to be actuated under control of the counter mechanism of said first calculator for shifting selected switches to said circuit closing position for connecting selected first conductors to selected second conductors so that one actuator of each group is energized by the correlated secondary winding independently of the other secondary windings when the first conductor connected thereto is connected to one of said second conductors whereby a plurality of actuators can be simultaneously energized by different voltage sources.
